UNITED STATES PATENT OFFICE

WILLIAM OGLESBY PASSMORE, OF LIVERPOOL, ENGLAND, ASSIGNOR TO ASSOCIATED TELEPHONE AND TELEGRAPH COMPANY, OF KANSAS CITY, MISSOURI, A CORPORATION OF DELAWARE

TELEPHONE SYSTEM

Application filed October 1, 1928, Serial No. 309,584, and in Great Britain November 8, 1927.

The present invention relates to telephone systems in general but is more particularly concerned with small automatic exchanges such as will often form private installations.

5 The main object of the invention is to provide a system of this type which will require the minimum amount of apparatus for discharging all the necessary functions and which shall also be very reliable so that little or no 10 attention is needed to maintain it in satisfactory order.

According to one feature of the invention a reduction in the amount of apparatus required is effected in that connection is adapted 15 to be made with both calling and called parties over the wipers of the same switch, all of said wipers being rigidly connected together.

According to another feature of the invention, a two-directional switch is employed 20 having a capacity equal to the square of the total number of lines in the system, connection being effected with the calling line on the first motion and with the called line on 25 the second motion of the switch.

Another feature of the invention is the use 30 of a two-directional automatic switch of the vertical and rotary type having its bank contacts arranged in levels and having two sets of wipers, the contacts engaged by one set 35 being multiplied vertically throughout the bank, while those engaged by the other set are multiplied horizontally throughout the bank.

Still another feature of the invention is the provision of an automatic switch adapted to 40 move its wipers to perform a hunting operation to connect with a calling line and subsequently to again move said wipers in response to impulses transmitted from said line.

These features will be better appreciated from the following detailed description of 45 one method of carrying the invention into effect which should be taken in conjunction with the accompanying drawings. It will be understood however that the arrangement described is given by way of example only and that various modifications to the circuit details could be made by those skilled in the art 50 without exceeding the scope of the invention.

The system considered is assumed to comprise 10 lines only, and it is assumed further that for such a system two connecting circuits will be sufficient to meet ordinary requirements, though if necessary one or more additional circuits can be added at any time without difficulty. A connecting circuit comprises 55 a two-directional switch of the well-known vertical and rotary type having six wipers each with a 100-point bank and also a vertical wiper for controlling the hunting operation 60 of the switch. The sequence of operations is that when a subscriber removes his receiver to make a call, the next available switch operates vertically to find his line with which connection is made over one set of three wipers and the switch is then rotated by dialled impulses to connect with the wanted party's line 65 over the remaining three wipers. Owing to the special arrangement of bank multiplying 70 which will be described fully subsequently, when connection has once been made with a calling line it is maintained with this line over the finding wipers throughout the rotary motion. 75

Referring now to the drawings comprising Figs. 1-5, Fig. 1 shows the line and instrument circuit of the subscriber A; Fig. 2 shows the circuit of a connector, it being understood that there are two such connectors or 80 more if the calling rate is very heavy; Fig. 3 shows the relays necessary for the generation and interruption of the various signalling tones; Fig. 4 shows the commoning of the banks engaged by the wipers for connecting with the called party, while Fig. 5 shows the commoning of the banks in which calling lines terminate. The drawings should be placed so that Fig. 2 is to the right of Fig. 1 and Fig. 3 is below Fig. 2, with the corresponding lines in alignment. 85

When the subscriber A lifts his receiver to make a call, the start relay S of which only one is provided, is operated from earth on resting armature 13, switch-hook springs 12, 95 impulse springs 10, transmitter TR, receiver RE, resting armature 15, resistance 11, conductor 20, winding of the start relay S to battery. This earth is also extended over resting armature 14 to the contact associated 100

with the line of subscriber A in the vertical test bank. The operation of start relay S extends earth from armature 19 over armature 27, normally closed vertical magnet interrupter springs 22, armature 39, lower winding of relay D to battery. Relay D operates and at armature 40 completes the circuit of the vertical magnet VM over armatures 31, 46 and 24, relay E also operating in shunt with the magnet to disconnect the busy tone circuit at armature 49 and to open the release magnet circuit at armature 53. The vertical magnet energizes and raises the wipers 16-18, 21 and 60-62 one step thereupon bringing the test wiper 21 into contact with the first contact of the vertical test bank. The opening of the vertical magnet springs 22 releases relay D and the restoration of relay D opens the circuit of the vertical magnet which releases closing its springs 22 and again completing the circuit of relay D. This interrupter action between relay D (which is slightly slow releasing as its upper winding is short-circuited by armature 38 of relay PA) and the vertical magnet is continued till the test wiper 21 encounters the contact in the vertical bank which has been earthed over the calling subscriber's loop. When this occurs relay FG will operate from this earth over the resting armature 28 of relay BA. The circuit for the vertical magnet is now opened at armature 46 and a circuit is completed instead for rotary magnet RM. The rotary magnet operates and steps the wipers 16-18 and 60-62 on to the first set of contacts, at the same time moving wiper 21 away from its bank so that relay FG de-energizes. Earth from wiper 17 now operates the cut-off relay CO and also serves to guard the calling subscriber in the called banks of the connectors. The operation of cut-off relay CO opens the circuit of the start relay S which restores thereupon opening the circuit of relay D, and also removes earth from the vertical test bank contacts. As the wipers are now engaging the first set of contacts, the circuit of impulse relay A is completed and relay A operates over the calling loop, thereby operating relay BA at armature 23 and this in turn operates relay B at armature 30. The operation of relay BA prepares a new circuit for relay FG at armature 28, at armature 29 prepares the holding circuit for the ringing trip and switching relays, and at armature 31 prepares the impulsing circuit to the rotary magnet. Relay B upon operating, at armature 24 disconnects the vertical magnet, at armature 25 opens the release magnet circuit; at armature 26 earths conductor 78 to start the busy tone, ringing and interrupter relays and at armature 27 switches the start lead to lead 77 extending to the second connector group so that another caller may take this second circuit.

It will be convenient to consider in detail

the operation of the tone and ringing relays at a later stage, and it will suffice for the moment to say that an intermittent howler or similar tone is available on conductor 74 for calling an intermittent tone on conductor 76 for busy signal and a similar but continuous tone on conductor 75 as a dialling signal.

The subscriber now hears a continuous tone connected up from conductor 75 over condenser 48 and resting armature 33 to his line and instrument and this is an indication that he may commence to operate his calling device. It will be noted that the switch has made an initial rotary step in its finding operation and under these circumstances it is necessary to absorb the first dialled impulse in order to retain the full availability of the banks. The first impulse therefore operates the two-step relay PA, and the remaining impulses are then transmitted to the rotary magnet. Impulse relay A responds to the impulses from the calling device, and on its first restoration extends earth from resting armature 23 over armatures 25, 47, 58 and 36, lower winding of two-step relay PA to battery. Relay PA closes its light tensioned armature 35, thereby short-circuiting its upper winding to earth on off-normal springs 41 until relay A re-energizes. Relay PA then operates all its armatures, and at armature 33 disconnects dialling tone from the subscriber's line, at armature 37 completes the circuit for the remaining impulses to be routed to the rotary magnet and at armature 38 removes the short-circuit from the upper winding of relay D. The rotary magnet responds to the remainder of the impulses over a circuit which may be traced from earth, armatures 23, 25, 47, 58, 31, 37 to the rotary magnet to battery and steps the wipers round in known manner to the desired line, relay E energizing in parallel with the magnet and providing an alternative circuit for the rotary magnet at armature 52 in case relay FG should operate as the test wiper 60 passes over a busy contact. Relays BA and E being of the slow releasing type, both remain in the operated position during the impulsing of relay A.

The wipers 60, 61 and 62 are now resting in engagement with the line of the desired subscriber, while it will be noticed that due to the commoning of the bank associated with the finding wipers 16-18 as shown in Fig. 5, connection is still maintained with the originating subscriber over these wipers. If the called subscriber is already engaged either as calling or called party, wiper 60 will encounter earth which is extended over armature 32, armature 50 before shunt relay E releases, armature 28, winding of relay FG to battery. Relay FG operates thereupon at armature 45 preparing a locking circuit for itself which will become effective when shunt relay E releases, at armature 47 opening the

5 rotary magnet circuit to prevent any further impulses affecting the rotary magnet, and at armature 44 completing a tone circuit from intermittent tone conductor 76, condenser 54, armatures 49 and 44, to the calling subscriber's line. The calling subscriber hearing the intermittent tone accepts this as an indication that the wanted subscriber is busy and replaces his receiver allowing the switch to 10 return to normal as described later.

10 If the wanted subscriber is free, no earth is encountered by test wiper 60 and as soon as shunt relay E releases, a circuit is completed for switching relay H from earth, armatures 29, 34, 45, lower low resistance winding of switching relay H, armatures 50 and 32, test wiper 60 to battery through the called subscriber's cut-off relay such as CO. The 15 cut-off relay operates to clear the called subscriber's line of its normal earth and battery connections, and switching relay H closes its light tensioned armature 57 thus completing the circuit of its second and locking winding which serves to operate all its armatures. 20 Switching relay H opens the rotary magnet circuit at armature 58 to prevent the rotary magnet being operated by any further impulses, at armature 56 extends full earth to the test wiper 60 for guarding purposes, and 25 at armatures 55 and 59 extends the ringing or howler circuit to the called lines. An intermittent loud tone is now connected from conductor 74, upper coil of ringing trip relay F, armatures 41' and 55, wiper 61, called 30 subscriber's line and instrument, wiper 62, armatures 59 and 43 to earth, relay F not being operated with this current. The loud tone actuates the receiver at the wanted station calling the attention of the subscriber. 35 It will be appreciated that ringing current to actuate a bell at the desired instrument could be connected in a precisely similar manner, but the arrangement of the kind described would probably be entirely satisfactory in a system of the kind considered with a saving in the cost of the subscribers' bells. 40 An indication to the calling subscriber that the wanted party is being called is afforded by the leak condenser 51 connected between the calling subscriber's talking condenser and the outgoing ringing or howler circuit.

45 When the called subscriber lifts his receiver to reply to the call, a direct current bridge is completed across his line and this causes relay F to operate its light tensioned armature 81 and complete a circuit for its second and locking winding. Relay F now operates all its armatures, thereupon at armatures 41' and 43 extending the circuit of the calling subscriber to that of the called subscriber by way of the speech condensers 80 and 82. Battery feed for the called subscriber's instrument is supplied by relay D, 50 which is connected across the called sub-

scriber's line and conversation can now take place.

The release of the switch takes place when the calling subscriber replaces his receiver. The circuit of impulse relay A is thus broken and in turn relay BA releases and opens the circuit of relay B. The circuit of the release magnet Z is then completed from earth, armatures 23, 25 and 53, off-normal springs 42, winding of release magnet Z to battery. 75 The operation of the release magnet Z restores the shaft and wipers to normal position where the off-normal springs are opened and the release magnet circuit broken. Relays F and H restore as their holding earth 80 relay PA restores when the shaft is normal and has opened the off-normal springs 41.

The production of the various tone signals may now be considered in more detail. As 85 mentioned above, the tones themselves are generated and the necessary interruption provided by means of relays. When the connector switches through on finding the calling subscriber's line, earth is connected to the 90 tone and interruption circuits over conductor 78. Considering first the busy tone circuit, relay BR, Fig. 3, is operated by this earth and at armature 63 breaks its own circuit thereby setting up a rapid self-interrupting operation. A conductor connected to the centre point to the two windings of relay BR is taken over armature 73 of relay I³ of the interrupter equipment to conductor 76, this arrangement providing an intermittent tone 95 on the conductor 76, the design and adjustment of relay BR giving tone of the desired frequency. The action of the howler tone relays R and V is somewhat similar and will be readily followed from the drawing, relay 100 V it will be noticed, short-circuiting itself when it operates. The arrangement is such that an intermittent tone of suitable strength and frequency for calling the wanted subscriber is supplied to conductor 74, and also 105 a similar but continuous tone is supplied to conductor 75 and this when passed through the low capacity condenser 48 is suitable as a 110 dialling indication.

The interrupter group of relays consists of 115 three slow acting and releasing relays I¹, I² and I³ so arranged that they operate each other in turn, the last one to operate releasing the first which then releases the second and in turn the third. This sequence of operations continues indefinitely and at a constant rate, the circuits requiring to be interrupted being taken through armatures on the relays. Earth on the starting conductor 120 operates relay I³ by way of armature 67, and this relay locks itself at armature 70 and at armature 71 completes the circuit for relay I² to operate. Relay I² locks itself at armature 69 and at armature 68 completes the circuit for relay I¹, which operates locking 125 130

itself at armature 66. The operation of relay I^1 shunts relay I^3 at armature 65, and opens the operating circuit of the same relay at armature 67. Relay I^3 upon releasing shunts relay I^2 at armature 70 and relay I^2 in turn releasing shunts relay I^1 . When relay I^1 is normal, the operating circuit for relay I^3 is again completed and thus the sequence will be repeated as long as the starting conductor is earthed. Armature 72 on relay I^2 interrupts the ringing or howler tone circuit and armature 73 on relay I^3 interrupts the busy signal circuit.

What I claim as new and desire to secure by Letters Patent is:—

1. In an automatic switch, two sets of wipers for connecting respectively with calling and called lines, and means including both sets of wipers for extending a connection from a calling line to a called line. 75
2. In an automatic switch having a plurality of wipers controlled by the same stepping magnets, means for automatically operating the stepping magnets to extend a connection to a calling line via certain of said wipers, means thereafter effective for directly operating one stepping magnet to extend a connection to a called line via other of said wipers while maintaining said first connection intact. 85
3. In an automatic switch having two sets of wipers mounted on the same shaft, means for moving the shaft to cause one set of wipers to connect with a calling line, and means for again moving the shaft to cause the other set of wipers to connect with a called line while maintaining the connection with the calling line intact. 90
4. In an automatic switch having two sets of wipers mounted on the same moving element, means for operating said element to connect with a calling line via one set of wipers, and means for reoperating said element to connect with a called line via the other set of wipers while maintaining said first connection intact. 95
5. In a telephone system, a line, an automatic switch having access to said line in a plurality of different positions, and means for operating said switch to connect with said line in a particular position determined by whether the line is calling or being called. 105
6. In a telephone system, a line, an automatic switch having access to said line in two different positions, and means for operating said switch to connect with said line in one or the other of said positions depending on whether the line is calling or being called. 110
7. In a two-directional switch for connecting with calling and called lines, means for selecting a calling line responsive to the first motion of the switch, and means for connecting with a called line responsive to the second motion of the switch. 115
8. In a telephone system, a two-directional switch having a capacity equal to the square of the number of lines in the system, means for selecting a calling line responsive to the first motion of the switch, and means for connecting with a called line responsive to the second motion of the switch. 120
9. In a telephone system, an automatic switch having two sets of wipers, a bank of contacts engaged by each wiper set, each bank comprising a plurality of vertically disposed rows of horizontally placed contacts, multiple connections between corresponding contacts of the respective rows in one of said banks, and multiple connections between adjacent contacts in each row in the other of said banks. 125
10. In a telephone system, an automatic switch having wipers, means for moving said wipers to establish a connection with a calling line, and means for subsequently moving said wipers responsive to directive impulses transmitted over the calling line while maintaining said first connection intact. 130
11. In a telephone system, an automatic switch having two sets of wipers, means for establishing a connection with a calling line via one set of wipers, and means effective responsive to such connection for establishing a connection with a called line via the other set of wipers. 135
12. In a telephone system, an automatic switch having two sets of wipers, means for establishing a connection with a calling line via one set of wipers, means effective responsive to such connection for establishing a connection with a called line via the other set of wipers, and means for connecting a signalling current to the called line. 140
13. In a telephone system, a line comprising two conductors terminating in a set of contacts accessible to an automatic switch, a test contact for said line, and means responsive to a call on said line for connecting a characteristic potential to said contact via the calling line loop. 145
14. In a telephone system, a line comprising two normally disconnected conductors, a potential connected to one of said conductors, a test contact connected to the other of said conductors, and means for connecting said conductors responsive to a call on said line. 150
15. In a telephone system, a line comprising two talking conductors extending from a subscriber's station and terminating in a set of contacts accessible to an automatic switch, a test contact for said line connected to one of said conductors, a source of direct current connected to the other of said conductors, and means responsive to a call from the station for connecting a direct current bridge across said conductors. 155
16. In a telephone system, a line comprising two conductors terminating in a set of contacts accessible to automatic switches, a 160

test contact individual to said line, a common start relay for said switches connected in multiple with said test contact, and means responsive to a call on said line for connecting a characteristic potential to said contact and said relay via the calling line loop.

17. In a telephone system, a plurality of subscribers' lines each comprising two talking conductors terminating in line contacts accessible to automatic switches, a test contact for each line connected to one of the talking conductors, a starting conductor for the automatic switch common to all lines, and multiple connections including a resistance individual to each line from said starting conductor to the said talking conductor of each line.

18. In a switching mechanism having an automatic primary hunting movement and a directly controlled secondary movement for extending connections between calling and called lines, a primary stepping magnet, and a relay for initially controlling the operation of said magnet and for subsequently feeding talking current to the called line.

19. In a vertical and rotary switch having access to calling and called lines by way of wipers, means for initially automatically moving the wipers into engagement with a calling line, said initial movement comprising one or more vertical steps and one rotary step of the wipers, and means for directly moving the wipers into engagement with a called line responsive to impulses transmitted over the calling line, said directive movement comprising one step less than the number of directive impulses transmitted.

20. In a vertical and rotary switch having access to calling and called lines by way of wipers, means for automatically imparting one or more vertical steps and one rotary step to the wipers to effect engagement with a calling line, means for receiving a series of directive impulses from the calling line, means for cancelling the first impulse of the series, and means responsive to the subsequent impulses of the series for imparting a corresponding number of rotary steps to the wipers to effect engagement with a called line.

21. In a two-directional switch having vertical and rotary stepping magnets, means effective for operating the vertical magnet only to perform an automatic hunting operation, and means effective for directly operating the rotary magnet to complete a connection.

22. In a two-directional switch, a vertical stepping magnet operated only automatically for controlling the primary motion of the switch, and a rotary stepping magnet automatically operated in its first step and directly operated in its subsequent steps for controlling the secondary movement of the switch.

23. In an automatic switch having move-

able wipers, means for moving said wipers to establish a connection with a calling line, and means for subsequently moving said wipers while maintaining said connection intact.

24. In an automatic switch having access to calling lines by way of wipers, means for stepping the wipers into engagement with a calling line, and means for further stepping the wipers while maintaining the connection with the calling line.

25. In a switch for establishing connections with calling lines by means of wipers, automatic means for stepping the wipers into connection with a calling line, and directly controlled means for further stepping the wipers while maintaining the connection established with the calling line.

26. In a telephone system, a line terminating in a set of contacts, a switch, means for automatically operating said switch to connect with the line via said contact set, means directly controlled over the line for further operating said switch, and other contact sets multiply connected with said first contact set for maintaining the connection between said line and said switch during the directive operation thereof.

27. In a telephone system, a line terminating in a plurality of multiply connected contact sets, a switch having wipers adapted to connect with said line via said contact sets, and means controlled over the line for directly operating said switch while the wipers move over said contact sets.

In testimony whereof I have signed at Liverpool, England, this 11th day of September, 1928.

WILLIAM OGLESBY PASSMORE.
